UNITED STATES PATENT OFFICE.

NICHOLAS J. HOLT, OF HOWELL, AND JOHN LEACH, OF DETROIT, MICHIGAN.

IMPROVEMENT IN CLAMPS.

Specification forming part of Letters Patent No. 140,136, dated June 24, 1873; application filed April 24, 1873.

To all whom it may concern:

Be it known that we, NICHOLAS J. HOLT, of Howell, in the county of Livingston and State of Michigan, and JOHN LEACH, of Detroit, in the county of Wayne and State of Michigan, have invented a new and useful Improvement in Clamps; and we do declare that the following is a true and accurate description thereof, reference being had to the accompanying drawings and to the letters of reference marked thereon and being a part of this specification, in which—

Figure 1 is an elevation of our clamp. Fig. 2 is a longitudinal vertical section of the same extended. Fig. 3 is a cross-section at *x x* in Fig. 2, and Fig. 4 is a bottom plan.

Like letters refer to like parts in each figure.

This invention has for its object to afford a convenient, powerful, but simple and inexpensive clamp, for the use of chair and cabinet makers and joiners; and it consists in the peculiar construction and arrangement of the several parts, as is more fully hereinafter set forth.

In the drawing, A A' represent triangular bars, both hollow on their under faces, and the latter adapted to slide over the former, each

bar being hooked at the outer end, as shown. The inner end of the bar A is provided with a yoke, B, through which the bar A' slides. In a recess or in a socket in the top of the yoke I pivot the lower end of a lever, C, in a slot in which, above the pivot, passes one end of a bar, D, whose other end is pivoted to a pin, a', transversely inserted through a longitudinal slot in the back of the bar A'. There are several pin-holes through the slot in this bar, through either of which the said pin may be inserted to increase or decrease the space between the jaws of the clamp. When thrown down over the bar A the lever C acts as a cam, to draw the clamp-bars together.

The inner faces of the jaws may be grooved or recessed to receive rubber or leather facings to prevent the marring of the articles which are clamped together by this device.

What we claim as our invention, and desire to secure by Letters Patent, is—

The clamp-bar A having the pivoted lever C with bar D attached thereto, in combination with the sliding clamp-bar A', as described.

NICHOLAS J. HOLT.

Witnesses: JOHN LEACH.
